UNITED STATES PATENT OFFICE.

NATHANIEL G. WARTH, OF COLUMBUS, OHIO.

TELEPHONE REPEATER SYSTEM.

No. 864,713.

Specification of Letters Patent.

Patented Aug. 27, 1907.

Application filed January 25, 1907. Serial No. 354,038.

To all whom it may concern:

Be it known that I, NATHANIEL G. WARTH, a citizen of the United States, residing at Columbus, in the county of Franklin and State of Ohio, have invented 5 a certain new and useful Improvement in Telephone Repeater Systems, of which the following is a specification.

This invention relates to improvements in telephone current repeaters or relay re-inforcers and systems for 10 their operation of the general character illustrated in the United States patents to Herbert E. Shreeve, as follows: Nos. 791,655 and 791,656 dated June 6, 1905, and 835,037 dated November 6, 1906, and is a modified form of and analogous in its major principles to the repeater apparatus and system disclosed in my patent of the United States No. 845,282, dated February 26, 1907.

The present invention like that covered by my patent above referred to involves conditions of operation and 20 accomplishes beneficial results in providing a constant balance for the repeater apparatus, regardless of the state of balance of the line circuits connected with the repeater for the purpose of preventing the local self-action known as "howling" or "singing"; effecting 25 the elimination of auxiliary coils and condensers, derived or balancing circuits, &c., which interfere with transmission by producing distorting reactive currents and cause an unnecessary dissipation of the current.

The important feature of my present improvement 30 is the arrangement and location of the line repeating induction coil windings in the sections of the line circuit, whereby direct through or original transmission from the transmitting station is reduced to a minimum. This condition is also largely contributed to by my use 35 of a very low resistance "bridge" between the two sides of the line, in which no repeater coils or windings are included, and which contains no repeater apparatus, but when the line circuit is also used for composited service, which combination is with this repeater system 40 especially contemplated, a condenser may be included in the bridge. This arrangement, together with my combination of divided or bridged local circuits, effects a condition of minimum direct transmission across the repeater station of the system, thus insuring 45 singleness of action and giving a clear reproduction and amplified re-transmission into the receiving end or section of the two sections of line circuit. This system, it will be noted, is also similar to that embraced in my patent mentioned above, in that the re-transmission being divided is effected simultaneously in both 50 directions or line circuit sections.

Another important object of the present invention is to secure an equalized transmission toward each terminal station, and particularly to prevent a line section 55 of low resistance from taking a disproportionate amount of the retransmitted current, each line section thus re-

ceiving practically half of the induced currents, which works to the advantage of the longer or higher resistance line circuit section. This is an advantage over the form embraced in my patent referred to, in which the 6 re-transmitting currents may divide inversely to the resistance of the two connected lines or circuit sections. This equalized or regulated division of the re-transmitted currents is secured by their creation or generation separately and equally in each line or circuit section, 6 and being confined therein by the low resistance bridge. The resistance of the associated circuit and its coils offers an additional barrier to overflow or direct transmission from line section to line section, and these conditions in association with the divided local circuits, 7 to be described hereafter, practically prevents such action and also that of the initial or originating currents being conductively transmitted into the associated section of line circuit past the repeater. These conditions produce the hereinbefore mentioned singleness of action or effect upon the repeater-receiver, and effectually 75 avoid echo like reaction currents, and distortions of the currents by the repeater apparatus.

While the invention chiefly consists in the above features it further consists in the provision of a peculiarly arranged composite toroidal form of repeating induction and retardation coil, whereby and wherein reactance or retarding effects are minimized for the telephonic or voice currents, and also for any direct or through transmission of composited or superposed 80 currents applied to the same line wires. For the latter class of service the invention also consists in auxiliary apparatus and circuit arrangements associated with the composite coil whereby "phantom circuit" or additional superposed currents, or service, 90 is especially provided for and enables the phantomed telephone (or simplex) transmission to pass the repeater station without interference and with no interference to the other simultaneous transmissions. This special induction coil is the common or dual means for the operative association of the repeater apparatus with the line circuit or circuit sections for both the receiving and re-transmitting currents. The secondary windings of the coil are preferably divided into four helices, two of which are symmetrically disposed on quarter 95 sections, on each half of the ring core, each pair of windings being differentially but conductively connected together in the through line circuit serially, one winding or helix on each side of the bridge, on each side of the line. These windings are the secondary or 100 main line windings of the coil, and are traversed by the telephonic or voice currents, the telephonic signaling or ringing currents, and, when the circuit is utilized for superposed or composited service, also for those currents, whether they be direct, pulsating or alternating in character.

When ringing currents, composited telegraphic, or

- 2
- signaling currents, are transmitted, either alone or simultaneously with the telephonic currents, the repeater apparatus being in circuit, is ordinarily subjected to more or less violent and undesirable action.
- 5 This action or effect in my arrangement is practically overcome, or rather is avoided by the differential windings referred to above, and which will hereinafter be more particularly explained in connection with other features of the arrangement of the coil and its connections.
- A great desideratum in connection with extending the range of telephonic transmission by means of a repeater, is the flexible use of the apparatus by the ordinary switching operators, whereby with a repeater apparatus installed in a "cord circuit", operators may arbitrarily or without any fine discrimination as to the resistances or other peculiar conditions, connect two circuits together, as readily as is ordinarily the operation of connecting two lines; or with no more judgment or effort on their part than is usual when a connection is established by including an ordinary "repeating coil" in a "through" circuit. The equal division and predetermining of the division or creation of the re-transmitting currents in the two circuit sections, together with the condition of constantly maintained balance of the repeater receiving element against local action, renders my repeater arrangement highly efficient and peculiarly adaptable to such general switching service.
- 30 For economic reasons "long distance" circuits are frequently used for composite service, that is, telephoning, telegraphing, signaling, &c., simultaneously over the same wires. Usually the telephone circuit is operated as a metallic circuit, and the other or superposed circuits as "grounded" or earth-completed circuits. To adapt my repeater system and apparatus to such combined or composite service, and to do so with a minimum of mutual interference, and as a protection to the repeater apparatus proper, it is desirable to affect the efficiency of transmission of the superposed currents as little as possible, and to shield the repeater apparatus from action by the non-telephonic currents. As the repeating induction coil secondary windings are included in the line circuits in this instance, the superposed currents are transmitted therethrough. Such currents being usually of low frequency and great volume compared with telephonic currents, have time to quite thoroughly magnetize a core of the character used in such a coil. Such a core effect would cause the coil to seriously retard the superposed currents, especially since they must traverse two windings, one on either side of the bridge. Such an effect would (or would not, according to the current frequency) also set up or create an undesirable action upon the repeater receiver-transmitter. Both undesirable effects I practically overcome by connecting the two windings non-inductively, or differentially, to the through superposed currents and without affecting the telephonic currents because their circuit is completed through the bridge and passes through the windings in their line circuit section side of the bridge only as will be more particularly explained. Certain other advantages also accrue in this respect by utilizing the various windings of the composite coil to render the non-telephonic currents harmless to the repeater apparatus. Ringing currents, as with the telephonic currents, are usually applied to the metallic circuit, and their violent action would operate the repeater injuriously. This effect can be practically avoided by connecting the two "telephonic" windings of the coil, that is, one winding in each conductor on the same side of the bridge, non-inductively or differentially. Low frequency ringing currents in this instance would produce a neutral field or core effect and not set up a strong induced current to violently affect the receiver element of the repeater in its local circuit, because the local windings are in neutral inductive relation to the secondary or telephonic windings. The higher frequency telephonic currents however, due to the magnetic reluctance of the core, produce efficient converting action by reason of the windings creating a local magnetic field, each in its own quarter section of the core.
- While the differential connecting of the various coil windings, as stated, is the preferred arrangement, especially for the composite purposes, the windings may be connected co-operatively throughout or partially differential, as may be desired for different service conditions, as will be described.
- The drawings accompanying this specification, are diagrammatic, illustrating the invention in its simplest or elementary form and developments of that form to the preferred form, such drawings being so made to facilitate an understanding of the physical and superposed circuits and the composite coil connections.
- Figure 1 is a diagram illustrating a compound circuit for a telephone repeater composed of two line circuit sections conductively ending at a repeater station in a repeating induction coil, with a winding each upon the same core and also representing a local or primary circuit with its winding upon the core; Fig. 2 is a diagram illustrating a similar compound circuit, but equipped with condensers inserted at the middle of the secondary windings of the repeating induction coil, conductively or physically separating the two sides of each line circuit section, and with inductance or retardation coils physically connecting the circuit sections on each side, thus providing for superposed direct or through transmission on each side of the compound circuit; Fig. 3 is a diagram illustrating such a compound circuit provided with a composite retardation and repeating induction coil and a condenser which together fulfil, in a simplified way, all the functions of the apparatus and arrangement shown in Fig. 2 for both the telephonic repeater and composite services; Fig. 4 is a diagram representing the invention, particularly as to the telephonic or repeater conditions, illustrating my combination of divided repeater circuits, embracing the main or compound through circuits with the low resistance bridge; the repeater-receiver circuit in which the receiver is operated inductively by the initial transmission from the terminal telephones, and is in a state of maintained balance against, and inert to, its own repeater-transmitter currents; and the split or divided repeater-transmitter circuit, having the battery or current supply, and the repeater-transmitter element included in the dividing conductor of the circuit; Fig. 5 is a diagrammatic representation of a complete compound repeater circuit arranged for composite service, and having associated therewith the composite coil,

which for clearness is illustrated with each of the plural windings on separated sections of the ring core, the primary and the tertiary windings being shown on dotted sections of core to show the presence 5 of the core in such windings, and the connections arranged for the sectional inductive action or collective differential effects; Fig. 6 diagrammatically illustrates the main line circuits of the system with the associated apparatus therefor, embracing a flexible cord-circuit 10 and, in addition to the telephonic, repeater and composite circuits, an arrangement for a "phantom" circuit, or a special "simplex" circuit, also inductance and inductive shunts around the repeater for particular operating and service purposes.

15 In Fig. 1, as in all the views, L and L^2 signify two sections of a metallic telephone circuit, or two metallic circuits, which in each case are assumed to be inductively joined with a telephone-repeater apparatus.

20 In Figs. 1, 2 and 3 the coil windings C , C^2 , &c., represent the secondary windings for the repeater and P the primary windings.

25 W and W^2 signify one side of the through circuit, and W^3 and W^4 the other side of the circuit; W and W^3 , and W^2 and W^4 , corresponding to the L and L^2 sections respectively, in all the views, of the composite circuit.

30 CX signifies the core of the repeating induction coil and is shown in dotted outline in Figs. 1, 2 and 3.

35 My invention, as the views throughout show, contemplates the division of the through compound circuit into two telephonic circuit sections, each section being complete and terminating at the repeater station, wherever it happens to be connected or included in said through circuit by means of its repeating induction coil winding or windings, and this termination comprehends the connection between the windings 40 when they are separated by a short conductor, which may include a condenser, as is shown in Fig. 2.

45 In Fig. 2, D represents the short conductors and J and J^2 condensers in same, connecting the inner terminals of the coils C , C^3 , and coils C^2 , C^4 , respectively. To adapt a circuit, so physically separated, to direct or through transmission across the repeater station, especially for forms of direct current telegraphic service, the circuit sections L , L^2 are connected together 50 around the repeater apparatus or station, by the use of conductors A , A^2 , in which suitable inductance or retardation coils F , F^2 are included, as shown in Fig. 2. These coils F , F^2 serve to preserve the separation of the circuit sections telephonically yet permit the passage 55 of direct or low frequency, &c., currents.

60 The condensers J , J^2 , are required to separate the two sides of the circuit when the "composite" service, by which is meant the superposed currents, is separately operated on the two wires or sides of the circuit, as is illustrated in Figs. 5 and 6. Such currents, as is well known, are practically stopped by a condenser, but such condenser will permit the passage of high frequency, &c., currents. To simplify the apparatus for use in such combined service, and also for special 65 adaptation to the flexible handling and use of the circuits, as will be set forth in further description of Fig. 6, I prefer to use the arrangement shown in Fig. 3.

65 In Fig. 3 the repeating induction coil has the windings C , C^2 and C^3 , C^4 , on each side respectively of the circuit, connected together to form therethrough a con-

ductive through circuit, the windings so connected being differentially associated and serving also as inductance coils in lieu of the coils F , F^2 , which are here omitted. The short conductors D of Fig. 2 are, by this method of connecting the windings together, replaced by the short connection or bridge H , in which a single condenser J may be utilized to advantage in lieu of the two separate condensers of said view. Thus arranged the several circuits are operatively as distinct as when physically so.

70 The coils in Figs. 1, 2, and 3 have cores of the usual straight bar or open circuit form, and while such coils are not ordinarily as effective as coils having the ring or closed circuit form of core, the bar or open form of core has, when provided with the separated sectional 75 winding shown and described, the same functions as my special toroidal type of coil, which is divided into distinct plural electro-magnetic sections for independent sectional core effects.

75 In Fig. 4, the two circuit sections L , L^2 , together with the terminal stations S , S^2 , and the repeater equipment at the intermediate station, comprise a complete telephonic system for long distance communication requiring repeater service. In this view the coil windings are arranged in co-operative relation 80 and straight series connection.

85 The flow of the currents are conventionally shown as follows: primary currents by short solid arrows; initial or repeating line currents by long solid arrows, and reproduced or repeated line currents by broken 90 arrows. An initial transforming line current being set up at the telephone S^2 would at the intermediate or repeater station, traverse the repeating induction coil windings C^2 , C^4 , and the low resistance connection or bridge H , and would induce current (also indicated 95 by long solid arrows) by means of the tertiary windings T , T^2 , in the half G^2 of the repeater receiver (T) circuit, thus energizing said receiver. Neither the initial currents from the line, nor the currents induced therefrom, in either the primary or the tertiary windings or circuits, penetrate their respective associated 100 like windings or circuits, by reason of the low resistance dividing cross-conductors or bridges H , P and TX , respectively. The receiver T winding, of the repeater apparatus R is connected into the bridge 105 conductor TX , and the transmitter M of the repeater apparatus R , together with the local battery B , are connected into the bridge conductor P . The energizing of the receiver T actuates the transmitter M , 110 the two elements being in repeater relation to comprise the repeater apparatus R , which varies correspondingly the resistances of the divided primary or local circuits and enables battery B to set up reproduced currents in facsimile, to flow through the four 115 primary windings P . These primary currents in turn induce like currents, except as to higher potential, in the associated coil windings; first, for transmission through the two line sections to the terminals S , S^2 , and second, to create neutralizing currents in 120 the halves G and G^2 of the tertiary local circuit, for 125 the receiver T , and prevent therein the local self action known as "howling" or "singing" which would otherwise ensue. The various circuits and currents can be traced as follows: a local impulse set up in the primary circuit SP^2 , at the terminal telephone S^2 .

would cause a current flow in the secondary windings of the induction coil SC^2 upward (in the diagram), thence to the left in the line conductor W^2 , thence through winding C^2 of the repeating induction coil, 5 thence to the junction with the bridge conductor H , through the bridge to the junction with the line conductor W^4 , thence to the right to and through winding C^4 of the repeating induction coil, thence to the point of starting at terminal telephone S^2 . The passing 10 of the current through the windings C^2 , C^4 would induce a corresponding current to flow oppositely (see the inner long solid arrows) in the associated tertiary windings T^e , T^e , and that circuit as follows: Beginning at winding T^e at the top, flowing to the right 15 thence downward, in the G^2 circuit, thence to the left to and through winding T^e at the bottom to the junction with bridge conductor TX , through the bridge and receiver T therein, to the top junction of the bridge with the G^2 circuit and to the right to and 20 through winding T^e , the starting point. The receiver T being thus energized and actuating the transmitter M would set up a primary reproducing current flow as follows: Starting from the positive pole of battery B , in the bridge conductor P upward to and through 25 the transmitter M thence upward to the junction of the bridge with the B^2 , B^3 sides of the primary circuit. At said junction the current divides, flowing to the right through the B^3 circuit to and through the primary winding P^e associated with line windings C^2 , 30 hence around to and through the winding P^e associated with line winding C^4 , thence to the junction with the bridge P and thence to the negative pole of the battery. The other portion of the current flows to the left from the dividing point through the B^2 circuit, to and through the primary winding P^e associated with line winding C , thence around to and 35 through the winding P^e associated with line winding C^3 , thence to the junction with bridge P where it unites with the other current. The flow of this battery current through the primary windings induces a facsimile current in all the windings associated, and this induced current flows in the opposite direction to the inducing current (see the directions of the broken and short solid arrows respectively). For the 40 line circuits, the broken arrows are shown in the receiving or L section only. This particular secondary current is confined to that section of the circuit, the flow being clearly shown by the broken arrows, as follows: Starting at winding C flowing to the right to 45 and through the bridge H thence to the left through coil C^3 , thence through line conductor W^3 to the terminal telephone at station S thence returning through line conductor W to and through winding C to the starting point. A like flow occurs in the associated 50 circuit section L^2 , which under the circumstances is dissipated energy. Simultaneous and analogous inductive effects are produced in the divided tertiary circuit G , G^2 . The same broken arrows at the four T^e windings represent the induced current in this 55 circuit.

It will be observed that the primary windings P^e , P^e in the B^3 side of the primary circuit are so connected that the battery current flows to the left, as is also the direction of its flow in windings P^e , P^e , on the B^2 side 60 of the circuit. This arrangement, without changing

the straight connections for the associated windings on the L^2 side of the repeater, produces a flow of the induced current in the tertiary circuits in the same direction, (see the broken arrows directed to the right at the top) down at the right and to the left at the bottom, thence up at the left and down through the bridge TX and receiver T on the left side of the bridge conductor, thence up through the bridge and receiver on the left side of the bridge conductor. As the two sides of the circuit are balanced and the induced currents therein are also balanced, a condition of no difference of potential through the bridge is produced, resulting in no actual flow of current in the bridge and the receiver T , which neutral state, to the re-transmitted currents, leaves the receiver unenergized and silent, and the transmitter inert. It should be understood that the reciprocal of these current flows and effects occurs with each change in the direction of transmission or use of the line.

The arrangement of practical division of the main, 85 tertiary and primary circuits effectually prevents interfering reaction currents and effects, which in other repeater systems are present and cause distortion of the reproduced currents by out-of-phase or echo-like overflow or reactance currents, due to direct transmission into the section of the circuit then receiving, 90 hence each circuit section, main and local, and the apparatus as I describe it operates as independently as would be the case were the circuit sections physically separated, (which is also within the scope of my invention) and the resulting transmission is as directly induced into each line circuit as is the initially produced transmission at the terminal telephones.

Reaction currents and their interfering effects, as referred to herein, are particularly explained in my 100 patent above referred to, as also are the conditions which create the self-action effects producing howling.

Fig. 5 is adapted particularly to an explanation of the composite repeating induction and reactance coil, and to the composite service conditions heretofore mentioned. This induction and reactance coil is preferably of toroidal form with the core CX composed of a bundle of No. 22 annealed soft iron wires, as is now usual with good forms of repeating and induction coils, and the coil should be closely covered with a soft iron 110 shell or casing to concentrate the stray field and for protection against injury. The windings can be of any gage of wire and number of convolutions adapted to the desired use. The primary helices P^e should be wound next the core, each of the four sections equally 115 positioned on quarter divisions of the common core. For usual service conditions the winding for each section should consist of about one hundred and fifty turns of No. 19 gage double cotton-covered copper wire. The two outer helices on each section may be so arranged that the tertiary windings are either outside or between the primary and secondary helices, or they may be alternately positioned if the number of turns around the core are compensated. Each helix should consist of about twelve hundred turns of No. 27 wire, 120 and the resistance through two windings in series should not exceed one hundred and fifty ohms. In said view the primary helices are the inner or core windings, the secondary windings C , C^2 , C^3 and C^4 are in the center and the tertiary windings are outside. 125 130

Across the coil, from circuit section to circuit section, the secondary windings on each side are differentially connected, C with C² and C³ with C⁴, which provides for the least retardation to the passage of the superposed through currents on either side; as well as for the minimization of inductive action to the repeater local circuits. Across the diameter of the coil, at right angles to the before mentioned direction, the secondary windings on each side are also differentially connected, 5 C² with C⁴ and C with C³, which provides for a minimum of inductive action to the repeater local circuits, and consequent violence to the apparatus, from strong currents circulating in either line circuit section, as previously explained. The four tertiary windings T^c 10 correspond to the four secondary sections, and as suggested above can therewith be interchangeably alternated or associated. The windings, however, can under other circumstances be of larger wire, as their function is to operate the receiver T, which is in a low 15 resistance local circuit. The receiver may also then be wound with larger wire with some advantage. The application of the tertiary windings to the receiver T circuits, is such, on each side of the bridge, that a telephonic impulse in its secondary windings from a 20 line circuit section, will induce a coöperative flow of current in the two windings (T^c), the current being shunted through the bridge TX and receiver T by reason of the low resistance of the bridge. The local 25 fields created in the coil by the telephonic currents having been explained, it remains to be stated that these small magnetic fields are made more intense and efficient for this condition by the provision of the iron shell referred to, which concentrates the stray field in each section by providing a short return circuit. This 30 is true particularly with reference to the differential conditions. The four primary windings are also differentially connected on each side of the bridge, in this instance, bridge P, and the inductive actions are similar owing to the rapid variation of current which 35 40 the transmitter creates in the battery circuits B², B³, and correspondingly energizing the windings.

The several local conditions and effects are similar to those described in connection with Fig. 4. While the differential connections are preferred, throughout 45 the several circuits, yet it is practicable to vary them without departing from the essential features of the invention. The primary windings may be connected coöperatively throughout or cooperatively on one side and differentially on the other, and the tertiary windings 50 may be similarly varied. With the receiving element T of the repeater apparatus R, I prefer to employ the permanent magnet U for establishing its residual or initial magnetic field for sensitization. In this view the superposed service is a direct current telegraph circuit on each side of the through line circuit, which arrangement is usually termed "composite" as distinguished from "simplex" and "phantom." The conductive separation of the circuit sides is effected 55 at the repeater station by condenser J; at the terminal station S by condensers J¹, J²; and at the terminal station S² by condensers J⁴, J⁵, the telephonic circuit sections being, in this instance, the same as in Fig. 4, with the exception of these condensers. The telegraphic circuits have common ground connections in 60 E and E², and common sources of energy in batteries 65

TB and TB². The lower circuit in this view is defined as follows: From ground E to and through battery TB, thence to junction Y of the battery tap, thence to instrument K³, line wire W³, coils C³, C⁴, line wire W⁴, instrument K⁴, battery tap Y², battery TB², ground E² and earth return. The upper circuit is similarly defined between Y and Y² by way of the earth, thence from Y to instrument K, through line wire W, coils C, C², line wire W², instrument K², and thence to Y². 70

In Fig. 6 the repeater local circuits and apparatus are eliminated, as the scheme of this diagram has to do particularly with the conditions of circuit and apparatus for connecting the repeater secondary circuit into the line circuits and with the operation of the superposed circuits past the repeater. The terminals of the two telegraphic circuits are omitted to avoid detail. The flexible operation of the repeater by means of cord circuits is illustrated in this view, the outer terminals of the four secondary windings, C, C², C³, C⁴, being connected by cord conductors, Q, Q², Q³, Q⁴, to plugs V, V², V³, V⁴, thence to the line conductors W, W², W³, W⁴, by means of the jacks O, O², O³, O⁴, all respectively. In practice the cords, plugs and jacks would be of the usual combined form for metallic circuits and similarly associated on each side of the repeater, and with other equipment details well understood by those skilled in the art and unnecessary to illustrate. For economy in apparatus and simplicity of operation it is preferred that the secondary coils and the cord circuit equipment shown in the view shall be withdrawn from the through line circuit, for composite service use, but when the repeater is not required for that same through circuit, I provide the auxiliary conductors A, A, and A², A², 90 on each side of the circuit, containing proper inductance coils F, F². By this arrangement the slow acting superposed currents may traverse both the repeating induction coil windings and the auxiliary coils on each side of the circuit, thus securing a more 95 efficient circuit, and when so used such division of the superposed currents offers additional safety to the repeater apparatus. Should the secondary windings be required to operate coöperatively, or should it be desirable to prevent heating of the apparatus from the 100 strong superposed currents, such through currents may be caused to be transmitted through the auxiliary conductors by inserting condensers in the cord circuits. The foregoing provisions of the cord circuit, and auxiliary apparatus, permits circuits to be used 105 for the ordinary long distance telephone service when not required for through or repeater service, and also permits various similar repeater connections to be established between circuits at a station having repeater equipment. In practice the line circuits may be terminated at a test board where the composite apparatus is located and connections are usually made and the lines then extended to the switchboard for the 110 regular telephonic operation. The superposed telegraphic currents in this instance have their circuits, 115 as explained in connection with Fig. 5, excepting that at the repeater station they are passed through the secondary windings of the composite coil, and through the auxiliary conductors. 120

At the terminal stations S and S², the receivers N, 130

N^2 , are connected at the middle of their windings with conductors XC and XC^2 respectively, leading to apparatus X and X^2 , respectively, which, as herein stated, may be either telephonic or telegraphic apparatus operated by high frequency currents. If the apparatus used is telephonic, the connections leading out on the opposite side to the dead ends XE and XE^2 respectively, would connect with another and parallel telephonic circuit, while if the apparatus is telegraphic 10 in character the connections may be with another circuit, or with the earth, or otherwise; suffice it to state that such a superposed circuit is termed a "phantom" circuit if telephonic or a "simplex" circuit if telegraphic in character. If a current impulse is set up at instrument X^2 , assuming it to have a positive flow through the system as shown to its corresponding station X , it 15 will pass through the conductor XC^2 to the middle connection with receiver N^2 , where it divides and flows differentially through the split windings of said 20 receiver, and thence each half of the current will pass along its respective circuit as follows: The half passing upward through condenser J^4 will follow conductor W^2 to its junction with the auxiliary conductor I^3 , thence along that conductor passing through condenser J in 25 circuit in conductor I^3 , to the junction of conductor I^3 with line conductor W^3 , thence to and through condenser J^6 and the lower winding of receiver N , thence through conductor XC and instrument X to XE , and finally completing its circuit back to X^2 by any path 30 that may be provided for it as indicated above. The other half of the current will find a like path from receiver N^2 through condenser J^6 , line conductor W^4 , auxiliary conductor I^4 and its condenser I^2 , to and through line-conductor W , and condenser J^3 , thence 35 differentially to the first half through receiver N to and uniting again with the first half. Such currents will not affect the telegraphic or telephonic apparatus, as already sufficiently described herein, excepting as follows: The telegraphic apparatus first described is 40 too sluggish in action to respond to the character of currents applied to this additional circuit, and such currents are unable to penetrate the retardation coils usually associated with the telegraphic apparatus (not shown in the view) at each terminal; and as set forth, 45 the secondary windings of the repeater composite coil are also largely impermeable to such currents, especially when a current is divided and when more than one winding is in the circuit as herein, hence the special paths or shunts I and I^2 are provided in transposed 50 arrangement around the repeater and associated composite apparatus. This arrangement will more completely prevent overflow currents or direct transmission into the receiving line circuit from either terminal telephone S or S^2 . As an additional precaution against 55 such action condenser J in the bridge should be of ample electro-static capacity.

What I claim and desire to secure by Letters Patent is:

1. In a telephone system for the reproduction with increased power of the initially transmitted currents from terminal telephones, the combination of a telephone repeater receiver-transmitter, a main circuit, and a bridge at the repeater station dividing the main circuit into two circuits or two associated repeater line sections; a repeating induction coil at the repeater station having sectionally divided plural secondary and local windings, and

having the secondary winding divided between the two sections of the main circuit with said bridge connected to each side of the main circuit between said divisions of the winding; a local circuit embracing a part of said plural local windings for the repeater-receiver and a local circuit also embracing a part of said plural local windings for the repeater-transmitter, each said local circuit having a bridge dividing its plural windings, said plural windings being wound to correspond with the said secondary windings and adapted to produce substantially equal effects through said local circuit bridges, and all the windings in each division of said coil being mutually inductive; the repeater-receiver and the repeater-transmitter being in circuit in the bridges of their respective local circuits, and a battery also in the local circuit containing the repeater-transmitter; said repeater-apparatus being sensitive to the inducing initial line currents from each line section but insensitive and inert to its reproduced currents in the line sections, and to prevent local self action. 70 75 80 85

2. In a telephone repeater system, the combination of a repeater apparatus, a main telephonic circuit, a main bridge dividing said circuit, a repeating induction coil having its secondary in said circuit, windings of said secondary being included in said circuit on each side of said bridge, local circuits for the receiver and transmitter of said repeater apparatus, local bridges dividing said local circuits, the divisions thereof being electrically balanced, and each containing local windings of the said 90 coil associated with respective secondary windings thereof, one of said local bridges containing the repeater-receiver and the other local bridge containing the repeater-transmitter and a battery, means for rendering the receiver-transmitter operative inductively to the received currents, 100 but inoperative to the local and reproduced currents. 95

3. In a telephone repeater system, the combination of a repeater apparatus consisting of a receiver and a transmitter in repeater relation, a line circuit consisting of two circuit sections each inductively associated with said repeater receiver and transmitter, local circuits for the receiver and transmitter, a repeating induction coil having plural secondary windings in the line circuit, and having associated local windings for the repeater-receiver-transmitter, both secondary and local windings being on a common core, a condenser inserted between the secondary windings and connected to each side of the line circuit to inductively terminate the line circuit sections at the repeater apparatus, each of said line sections including separate secondary windings of said coil, said repeater receiver being maintained in a constant balance against local self-action and against unbalanced line circuit effects. 105 110 115

4. The combination, in a telephone repeater system, of a receiver and transmitter associated in repeater relation, a repeating induction coil having plural windings both secondary and local, a transmitting line having a section on each side of the repeater apparatus and inductively associated with the receiver-transmitter through said coil, the repeater-receiver being connected in circuit with the local windings in a constantly maintained balanced relation whereby it is rendered insensitive to its own battery currents but sensitive to the inducing currents from the line circuits and their associated secondary windings, the said secondary windings of the coil being divided between the line circuit sections, the divisions in each circuit section being operative therewith individually to insure singleness of transmission effects and proper division of current. 120 125 130 135

5. In a reciprocal telephone repeater system, the combination of a main transmitting circuit divided at a repeater station into two line circuit sections, terminal telephones associated therewith to originate currents for reproduction, and a repeater apparatus comprising an electro-magnetic telephone receiver and a variable resistance transmitter associated in repeater relation to receive the telephonic currents from one of the circuit sections and to transmit facsimile currents of greater power to the associated circuit section and the terminal telephone apparatus therein, a repeating induction coil having plural secondary and local windings, said secondary windings 140 145

- being in the line circuits and divided between and apportioned to the sections thereof, the repeater-receiver and transmitter both being connected in circuit with local windings of said induction coil and inductively associated therewith the line sections to furnish the reproduced currents to each of said circuit sections simultaneously. 85
6. In a telephone repeater system, the combination of a repeater receiver-transmitter, two line circuits, a repeating induction coil connected in the line and inductively joining the line circuits with both the repeater-receiver and transmitter, said repeating induction coil having a plurality of secondary windings divided between the two line circuits, and a plurality of local windings divided 90 between the repeater-receiver and transmitter whereby they are in local relationship to the line circuits, and both are in common inductive relationship with the secondary windings of said coil in the line circuits, and whereby each line circuit is supplied with the reproduced currents 95 from the repeater by its individual secondary windings, and the repeater-receiver is supplied with individual induced currents from each line circuit. 100
7. In a telephone repeater system, the combination of a main telephone circuit comprising two line circuit sections each section equipped with telephones, a repeater apparatus comprising a receiver and transmitter associated in repeater relation at an intermediate connecting point on the line for relaying the currents from one line circuit section to the other, a repeating induction coil having plural secondary and local windings at said intermediate connecting point on the line, the repeater-receiver and transmitter each being in circuit with separate local windings of the repeating induction coil, the secondary windings being associated with each other and 105 with the line as follows: a winding for each circuit section on each side of the line, the windings being connected to each line conductor individually at each side, the windings on each side having their other terminals connected and the connected terminals coupled by a low resistance conductor, thus providing individual secondary windings 110 for each line circuit section. 115
8. In a telephone system for reproducing the initial currents with increased power for extending the distance of transmission directly, a through compound line circuit comprising two telephone line circuits terminating in a repeating apparatus at an intermediate repeater station, a repeating telephone consisting of a receiver and a transmitter associated in repeater relation and a repeating induction coil having plural secondary and plural local 120 windings, a bridge of low resistance at the repeater station connecting the two through line circuits and terminating the line circuits; the secondary windings of said repeating induction coil being divided and apportioned to each line circuit but said windings collectively being in 125 operative relation with both the receiver and transmitter and receiving from and transmitting to the line circuits the telephonic impulses, the repeater-receiver and transmitter being in circuit with the local windings of said coil and adapted to be actuated only by the currents induced from each line circuit. 130
9. In a telephone repeater system, the combination of a main line circuit, a repeater, said main line circuit being divided into two circuit sections at the repeater, local circuits for the repeater receiver and transmitter, a repeating induction coil having secondary and local windings, the secondary windings being apportioned to the two line circuit sections and the local windings apportioned to the local circuits, both said receiver and transmitter being in direct inductive relation to the secondary windings of 135 said coil whereby said secondary windings serve in common for the inward and outward currents of the repeater receiver and transmitter respectively, the secondary windings at each side being connected to their respective line conductors, and said windings on each side having their other terminals connected, and such connected terminals being coupled by a condenser, forming a low resistance path 140 for the telephonic currents to traverse between the main line circuit conductors. 145
10. In a telephone current reinforcing system, the combination of a main telephone-circuit, a bridge connection 150 between the conductors thereof, a repeater apparatus comprising a receiving magnet and a variable resistance transmitter actuated thereby, a repeating induction coil interposed between said main circuit and the said repeater apparatus, said repeating induction coil having a secondary winding composed of four helices, each helix being wound over a separate section of a magnetic core, and connected in the main telephone circuit so that two divisions of the winding will be on each side of said bridge connection, and eight local helices divided into two groups of four substantially equal divisions and wound to correspond to the said secondary divisions, each section of the core thus having three helices; four local helices, one for each section of said core, a battery and transmitter circuit containing a bridge, two helices being connected together on each side corresponding to the two secondary helices on each side of said first named bridge, and each pair connected together and to the last named bridge conductor by their remaining terminals, so that said bridge conductor, its battery, and the variable resistance transmitter, will divide this primary circuit to correspond to the divisions of the secondary circuit; a third bridge conductor containing said receiving magnet with which the four remaining local helices are similarly connected. 155
11. In a telephone repeater system, a laminated iron ring core repeating induction and retardation coil, having four electro-magnetic sections, individual secondary and primary mutually inductive windings for each section, two secondary windings on each half of the core across one diameter being connected together for through transmission with two terminals for connection to the line, a bridge connected on each side to the joined terminals of the two said halves, said bridge connection being made to form two halves of the coil across a diameter at right angles to the aforesaid diameter of the core, the latter halves 160 being composed of one coil of each of the former halves, and together constituting four overlapping secondary circuits, adapted to be variously connected for inductive and non-inductive effects for single and simultaneous service. 165
12. In a telephone repeater system, a telephone repeater apparatus, comprising a repeater receiver and transmitter, two main telephone circuits or circuit sections, a cord circuit joining them, said cord circuit containing a repeating induction coil, divided secondary and local windings in 170 said coil, a portion of said secondary windings being in each circuit section when the cord circuit is in use, the repeater receiver and transmitter being directly connected in circuit with the local windings of said repeating induction coil, and inductively associated with the secondary windings of said coil, and with the main telephone circuits. 175
13. In a telephone repeater system comprising two sections of transmitting line, a repeater apparatus and instrument circuits local to said line and at an intermediate station thereon, the combination of means within said local circuits for establishing an electrical balance for the repeater 180 receiver, said means when operating as a balance being independent of the line to prevent the creation in the receiver of self-action effects tending to disturb the transmission and distort the form of the originating currents, said balancing means constituting a part of said instrument circuits, which circuits together with the repeater apparatus are connected inductively directly with the transmitting line, a repeating induction coil forming said inductive connection, said induction coil being divided in 185 its secondary to serve both sections of the transmitting line individually and also to operate the receiver inductively. 190
14. In a telephone repeater system, the combination of main and local circuits, the main and local circuits each being divided to form separate circuits to prevent the initial telephonic currents in said main circuit from being transmitted directly beyond the repeater, a repeater apparatus comprising a receiver and a transmitter in repeater relation, and a repeating induction coil, the secondary windings of which are in the main circuit and the local 195 windings of which are in circuit with the said repeater apparatus. 200
15. In a telephone repeater system, the combination of a main circuit and two local circuits, each of which is divided to form separate circuits, a repeating induction 205

- coil having its secondary windings divided between the divisions of the main circuit, and its local windings divided between the divisions of the two local circuits, and a telephone repeater apparatus directly associated with the said local windings and inductively associated with the said main circuit secondary windings.
16. In a telephone repeater system, the combination of main and local circuits each divided to form separate circuits, a compound induction coil for preventing reactive 10 distorting currents, the secondary windings of which are divided in service between the sections of a main telephone circuit, and the local windings of which are divided between the sections of the local circuits, a repeater apparatus associated with the local circuits, said coil being 15 the medium for both receiving and re-transmitting all the telephonic currents between said repeater apparatus and said main line, the repeater apparatus being connected in said local circuits in a constantly maintained balanced relation whereby it is rendered sensitive to the 20 received currents and inert to its own currents.
17. In a telephone repeater, a composite repeating induction and retardation coil having a plurality of secondary and local windings for transforming the telephone currents, each of said secondary windings being wound on a 25 separate section of the core and connected in a compound metallic telephone circuit, the several secondary windings being divided into conductively and inductively connected sections, the said sections being arranged to create overlapping magnetic fields and operative to create a conductive 30 differential condition in the coil for composite extra currents passing through on each side of the circuit, a bridging condenser connecting the conductively connected sections of the coil to form the inductively connected sections for the telephonic currents which terminate at the coil.
18. In a telephone repeater, the combination of an induction coil of ring core type, having four secondary windings, each on a separate section of the core, two of which on either side are connected conductively but non-inductively together to form non-inductive halves, a condenser 40 joining inductively said conductive halves to form two inductive halves, each of which is composed of one coil of each of the conductive halves, and mutually inductive local windings similarly disposed on the same core for transforming in connection with the secondary windings the 45 repeater-telephonic currents.
19. In a telephone repeater system, a telephone repeater apparatus including a local circuit in direct inductive association with the line conductors of the main line circuit, a bridge conductor dividing the local circuit, a battery and 50 a transmitter in circuit in the bridge conductor, and local windings in each side of the local circuit.
20. In a telephone repeater apparatus, the combination with a local circuit, of a bridge conductor in said local circuit, a battery and a transmitter in circuit in said bridge conductor, a second local circuit, and a receiver in said 55 second local circuit.
21. In a telephone repeater system, the combination of a main line having two metallic circuit sections associated with a repeating induction coil, a telephone repeater receiver-transmitter in circuit with the local windings of 60 said induction coil and in direct inductive relation to the secondary windings of said coil, and said main line sections being in circuit with the secondary windings of said coil, the secondary windings being divided and apportioned to 65 said main line sections for respective individual operation therewith, and auxiliary conductors provided with inductances forming shunts around the repeating coil for the through transmission of slow-acting currents and for the protection of the repeater receiver-transmitter.
22. In a telephone repeater system, the combination of a main telephone circuit, the two conductors of which are separately and jointly adapted for the transmission of 70 superposed currents, a telephone repeater station on said circuit, a bridge connection between the two conductors of said circuit at the repeater station, a repeater apparatus at said station comprising a receiving magnet and a variable resistance transmitter actuated thereby, a composite repeating induction and retardation coil inductively associating said main circuit and said repeater apparatus, said 75 coil having a magnetic core, and primary or local and sec-
- ondary windings, the secondary winding being divided into four helices each helix being wound over a separate section of the magnetic core and connected in said main telephone circuit so that two helices of the said secondary winding will be on each side of said bridge connection; two local circuits, one constituting a tertiary circuit divided by a bridge conductor containing the receiving magnet, and the other constituting a primary circuit divided by a bridge conductor containing the transmitter and a battery, each of said local circuits containing a division of said local winding, each division being divided into two groups, each group having four helices which are connected in pairs on each side of said bridge conductors, each group being wound to correspond in position to the helices of said secondary winding: each section of said magnetic core having 85 three helices, and each section constituting a distinct inductive electro-magnetic field; one helix from each of said divisions of said local winding forming one of said groups of helices, one helix of which group being on each section of the core and connected in circuit with said battery, thus 90 one pair of helices on each side of the coil is in corresponding position to the two secondary helices on each side of said main circuit bridge connection, and the pairs being connected to their local bridge conductor by their remaining terminals, so that the local circuit containing 95 the battery and transmitter will be divided by its bridge conductor to correspond to the said division and arrangement of the secondary circuit of said coil, the other group of four local helices being connected in said tertiary circuit and arranged similarly to the first group; an auxiliary conductor containing an inductance connected around the said secondary windings to the line conductors on each side of the main circuit, and conductors containing condensers connected around said secondary windings for 100 shunting therefrom high frequency through superposed currents.
23. In a telephone repeater system, a laminated iron ring core repeating induction coil having four electro-magnetic sections, individual secondary and primary mutually inductive windings for each section, two divided secondary windings on each half of the core, across one diameter, being conductively joined together and having two terminals for connection to the line, said windings being adapted to be variously connected, a non-inductance bridge connected on either side to the inner or joined ends 105 of the two said conductive halves to form two halves inductively connected by a condenser across a second diameter of the ring core at right angles to the first mentioned diameter, said latter halves being composed of one coil of each of the conductive halves and both together constituting 110 four overlapping secondary circuits.
24. In a telephone repeater system, the combination of a main telephone circuit, the two conductors of which are separately and jointly adapted for the transmission of superposed currents, a telephonic repeater apparatus associated with said circuit, a repeating induction coil inductively connecting said main circuit and said repeater apparatus, the repeater apparatus being connected in circuit with the local windings of said repeating induction coil, the secondary windings of said coil being connected in 115 the main circuit with two windings in each conductor thereof, each two windings being in series relation but differentially connected, a bridge containing a condenser interposed between the two main circuit conductors, and connected to said conductors between the two windings in 120 each of said conductors, condensers included in each conductor of the main circuit, shunting inductances connected in circuit around the secondary windings of the coil on each side, and condensers connected around said secondary windings and inductances to shunt from the repeater high 125 frequency through superposed currents.
25. In a telephone repeater system, the combination of a main telephone circuit, the two conductors of which are jointly and separately adapted for the transmission of superposed currents, a telephonic repeater comprising a 130 receiver and transmitter associated with said circuit, a repeating induction coil in the main circuit inductively connecting said main circuit and said repeater apparatus, the repeater receiver and transmitter both being connected in circuit with the local windings of said repeating induction 135 coil.

coil, and the secondary windings of said coil being connected in the main circuit with two windings in each conductor thereof, each two windings being in series relation but differentially connected.
